UNITED STATES PATENT OFFICE.

PHILIP A. MYERS, OF ASHLAND, OHIO, ASSIGNOR TO F. E. MYERS AND BROTHER, OF ASHLAND, OHIO, A COPARTNERSHIP CONSISTING OF FRANCES E. MYERS AND PHILIP A. MYERS.

SPRAY-NOZZLE.

1,121,654.

Specification of Letters Patent.

Patented Dec. 22, 1914.

Application filed December 14, 1911. Serial No. 665,632.

To all whom it may concern:

Be it known that I, PHILIP A. MYERS, a citizen of the United States, residing at Ashland, in the county of Ashland and State of Ohio, have invented certain new and useful Improvements in Spray-Nozzles, of which the following is a specification, reference being had therein to the accompanying drawing.

10 This invention relates to spray nozzles and the object of the invention is to provide a nozzle to produce a fan-like spray; which will be simple and durable in construction; and which can be adjusted to cause the fluid 15 to come in contact with different portions thereof, thereby providing a nozzle which can be manufactured at a relatively low cost and which will have a long life in the hands of the user.

20 In the accompanying drawings, Figure 1 is a plan view of a nozzle embodying my invention; and Fig. 2 is a vertical section, taken through the same.

In these drawings I have illustrated one embodiment of my invention and have shown the same as comprising two portions, one of which has a flat surface and the other of which has an opening communicating with the source of supply and so arranged 25 as to cause the fluid discharged therefrom to impinge against the flat surface of the first-mentioned portion of the nozzle. The flat surface of said first-mentioned portion extends to the outer edge thereof and, consequently, the fluid which comes in contact 30 therewith at an acute angle is discharged from the nozzle in the form of a fan-like spray. In the device here illustrated the nozzle is shown as comprising two disk-like plates 1 and 2 having their faces flat and fitting snugly together. The plate 1 is of 35 a diameter slightly less than the diameter of the plate 2 and has an opening 3 extending through the same at an acute angle to the face of the plate 2. The plate 1 has secured to the back thereof a socket 4 adapted to be connected with the supply pipe or hose and by means of which the opening 3 in the plate 1 communicates with the source of fluid supply. The arrangement of the opening 3 relatively to the plate 2 is such that the fluid 40 passing from the outer end thereof will come in contact with the adjacent portion of that plate. As here shown the opening is 45 formed in the plate 1 near the edge of the

inner face thereof and the edge of the plate adjacent to the opening is beveled, as indicated at 5, to permit the passage of the fluid. It will be noted that the socket 4 and opening 3 are both arranged at an acute angle to the face of the plate 1, and, consequently, the discharge opening for the nozzle is approximately in alinement with the socket and the supporting pipe or hose.

The action of the fluid, which is usually a chemical solution, will eventually pit the face of the member 2 so as to interfere with the proper formation of the spray. In order that the life of the nozzle may be lengthened and a satisfactory spray formed for a much longer period of time I prefer to make the member or plate 2 adjustable so that different portions of the flat surface thereof may be brought into alinement with the discharge opening 3 of the plate 1. In the present instance the plate 1 is provided with a central screw-threaded stud 6 upon which the plate 2 is pivotally mounted and upon which it is confined by means of a thumb nut 7. By loosening the nut the plates can be relatively adjusted to bring different portions of the surface of the one member into alinement with the discharge opening of the other member. I have also provided means whereby the nozzle can be freed from accumulations of matter should it become clogged. To accomplish this I have formed a notch 8 in one edge of the disk-like member 2 and by moving this notch into alinement with the openings 3 a straight, unobstructed passage is provided for the fluid and the matter which may have accumulated in the openings 3 may be forced out of the same, after which the member 2 may again be adjusted to produce the spray.

While I have here shown and described one embodiment of my invention this has been chosen for the purposes of illustration only and I wish it to be understood that I do not desire to be limited to the details of construction shown and described, for obvious modifications will occur to a person skilled in the art.

Having thus fully described my invention, what I claim as new and desire to secure by Letters Patent, is:—

1. A spray nozzle comprising two members arranged face to face and having their adjacent faces substantially flat, one of said members having an opening adapted to

- communicate with a source of fluid supply and arranged to discharge the fluid against the flat face of the other member at an acute angle thereto and at a point removed from that edge of said member toward which it is directed, said first member being partially cut away beyond said opening to provide an unobstructed space between the discharge opening and the edge of the first-mentioned member.
2. A spray nozzle comprising two members having their adjacent faces flat and arranged substantially parallel and in close proximity one to the other, one of said members having an opening adapted to communicate with a source of fluid supply and arranged to discharge the fluid against the flat face of the other member at an acute angle thereto and at a point removed from the edge thereof, one of said members being adjustable relatively to the other about an axis so arranged with relation to said discharge opening that said edge of said first-mentioned member will project beyond said discharge opening at all times when the face thereof is in alinement with said opening and will cause a spray to be discharged in substantially the plane of the face thereof.
3. A spray nozzle comprising two members having their adjacent faces flat and arranged in close proximity one to the other, one of said members having a curved edge and the other member having an opening adapted to communicate with a source of fluid supply, arranged at an acute angle to the face of the first-mentioned member and adapted to discharge the fluid against the face of and toward the curved edge of said first-mentioned member, said members being relatively adjustable about the axis of the curved edge of said first-mentioned member, whereby one portion of the face of said member may be moved out of alinement with said opening and another portion thereof presented to the fluid discharged from said opening and the edge of said member maintained at all times at the same distance from said discharge opening.
4. A spray nozzle comprising two members having their adjacent faces flat and arranged substantially parallel and in close proximity one to the other, one of said members having an opening adapted to communicate with a source of fluid supply and arranged to discharge the fluid against the flat face of the other member at an acute angle thereto and at a point removed from the edge thereof, one of said members being adjustable relatively to the other of said members to enable successive portions of the flat face of that member against which the fluid impinges to be moved out of the path of the fluid, and other portions of said flat face of said member to be presented to the fluid, that member against which the fluid impinges having a cut-a-way portion nor-
- mallly out of the path of the fluid and movable into alinement with said discharge opening to permit the unobstructed passage of the fluid therefrom.
5. A spray nozzle comprising two members, one of said members having a substantially flat face and the other of said members having an opening adapted to communicate with a source of fluid supply and arranged to discharge the fluid against the flat face of the first-mentioned member, at an acute angle thereto, and toward the edge thereof, one of said members being adjustable relatively to the other about an axis so arranged with relation to said discharge opening that said edge of said first-mentioned member will project beyond said discharge opening at all times when the face thereof is in alinement with said opening and will cause a spray to be discharged in substantially the plane of the face thereof.
6. A spray nozzle comprising two substantially circular members having their adjacent faces substantially flat and arranged substantially parallel one with the other, one of said members having an opening adapted to communicate with a source of fluid supply and arranged to discharge the fluid against the face of the other member at an acute angle thereto, said other member being adjustable about a substantially central axis and that member which has said opening being partially cut away beyond said opening to provide an unobstructed space between the discharge opening and the edge of said adjustable member.
7. A spray nozzle comprising a plate having a socket rigidly secured thereto and adapted to be connected with a supply pipe, an opening formed in said plate at an acute angle to the face thereof and communicating with said socket, the edge of said plate being beveled adjacent to said opening, a stud rigidly secured to said plate centrally thereof, a second plate mounted upon said stud, and a thumb nut to lock said plates in adjusted positions.
8. A spray nozzle comprising two members having their adjacent faces flat and arranged substantially parallel and in close proximity one to the other, one of said members being adjustable about a fixed axis and the other of said members having a relatively small opening adapted to communicate with a source of fluid supply and arranged to discharge the fluid against the flat face of the first-mentioned member at an acute angle and in a direction radial thereto and at a point removed from the edge thereof.
9. A spray nozzle comprising two members, one of said members having a flat face and the other of said members being arranged in close proximity to the first-mentioned member and having a relatively small

opening adapted to communicate with a source of fluid supply and arranged to discharge the fluid against the flat face of the first-mentioned member at an acute angle to the plane of said face to cause the spray to be discharged beyond the edge of said first-mentioned member in substantially the plane of the flat face thereof, and means to adjust one of said members relatively to the other to cause different portions of the flat

face of the first-mentioned member to be brought into the path of the fluid discharged from said opening.

In testimony whereof, I affix my signature in presence of two witnesses.
